US00D943161S

(12) **United States Design Patent** (10) **Patent No.:** **US D943,161 S**
Cheung et al. (45) **Date of Patent:** **** Feb. 8, 2022**

(54) **VAPORIZER DEVICE**(71) Applicant: **JUUL Labs, Inc.**, San Francisco, CA (US)(72) Inventors: **Brandon Cheung**, San Francisco, CA (US); **Carlos A. Dominguez**, San Pablo, CA (US); **Dylan E. Entelis**, Los Angeles, CA (US); **Matthew J. Malone**, Los Angeles, CA (US); **James Monsee**, San Francisco, CA (US); **Zachary T. Scott**, Oakland, CA (US); **John Travis Wettrath**, San Francisco, CA (US)(73) Assignee: **JUUL Labs, Inc.**, San Francisco, CA (US)(**) Term: **15 Years**(21) Appl. No.: **29/713,291**(22) Filed: **Nov. 14, 2019**(51) LOC (13) Cl. **27-02**

(52) U.S. Cl.

USPC ..... **D27/162**(58) **Field of Classification Search**

Primary Examiner — Rebecca Tsehay(74) *Attorney, Agent, or Firm* — Mintz Levin Cohn Ferris Glovsky and Popeo, P.C.(57) **CLAIM**

The ornamental design for a vaporizer device, as shown and described.

DESCRIPTION

FIG. 1 is a top, front, and right side perspective view of a vaporizer device of our design;

FIG. 2 is another top, front, and right side perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The dash-dash broken lines illustrate portions of the vaporizer device that form no part of the claimed design.

The dash-dot broken lines illustrate boundary lines that form no part of the claimed design.
